UNITED STATES PATENT OFFICE

HARRY H. STYLL, OF SOUTHBRIIDGE, MASSACHUSETTS

BRIDGE FOR OPHTHALMIC MOUNTINGS

Application filed December 15, 1927. Serial No. 240,150.

This invention relates to improvements in means for connecting the lens holding members of ophthalmic mountings and has particular reference to improved means for adjusting the said lens holding means to a required separation.

The principal object of the invention is to provide improved means for regulating the distance between the lens holding members of ophthalmic mountings.

Another object of the invention is to provide improved means for connecting the lens holding members of ophthalmic mountings which may be adjusted to regulate the distance between the lens holding means, at the same time being foldable.

Another object of the invention is to provide improved means for regulating the distance between the lens holding members of an ophthalmic mounting which will be foldable and at the same time adjustable as to the distance between the lens holding members by twisting.

Other objects and advantages of the invention will be apparent from the following description taken in connection with the accompanying drawings and it will be understood that many changes may be made in the arrangement of parts and details of construction without departing from the spirit of the invention as expressed in the accompanying claims. I, therefore, do not wish to be limited to the exact details of construction and arrangements of parts shown as the preferred forms only have been shown by way of illustration.

In that type of ophthalmic mountings usually known as protective goggles it has been customary to connect the two lens holding members by means of a chain so that simply by twisting one lens holding member with respect to the other the chain will be twisted and shortened thus changing the distance between the two lens holding members.

This has proved a very useful and practical

device. It has, however, one outstanding disadvantage, namely, that when the mounting is taken off the face of the wearer the chain untwists and the distance between the lens holding members is changed. In other words, the adjustment for the pupillary distance of the wearer is lost so that this pupillary distance has to be adjusted by twisting the chain each time that the wearer puts on the mounting.

In my improved device I preserve the flexibility of the chain bridge but I provide improved means therein by which the adjustment for the pupillary distance is maintained and not lost each time the mounting is taken off the face. With my device, therefore, the lens holding members may be folded with respect one to the other just as with the prior art chain bridge and the pupillary distance of the mounting be maintained.

Referring to the drawings:

Fig. 1 is a front view partially in section showing the invention with the lens holding members extended to their fullest separation;

Fig. 2 is a view similar to Fig. 1 showing the lens holding members adjusted closer together than in Fig. 1;

Fig. 3 is a top or plan view of Figs. 1 and 2;

Fig. 4 is a cross section on line 4—4 of Fig. 1;

Fig. 5 is a cross section on line 5—5 of Fig. 2;

Fig. 6 is a partial view similar to Figs. 1 and 2 showing a modification.

Referring to the drawings wherein similar characters of reference denote corresponding parts throughout, the lenses 1 are held in the lens holding members 2 which may be in the form of an eye cup as shown in Fig. 3, being cut along the line 3 to fit the face. The lens holding members may be held in place on the face by means of the head band or strap 4 secured to the lens holding members 2. On each lens holding member 2 is a staple 5 which may be bent or extended out as shown in Fig. 90

3 to allow more room for the nose. Fitting in the staple 5 is the ring 6 through which is passed a bendable wire bridging member 7 and over the bendable wire 7 is placed a nose engaging member 8 which is preferably a section of soft rubber tubing.

Fig. 1 shows the bendable wire 7 in the form of an open loop or link and this is the initial position of the member 7 with respect to the other members of the mounting. The operation of the device is as follows: If it is desired to shorten the distance between the lens holding members 2 the member 7 is twisted as indicated in Fig. 2. This twisting shortens the member 7. It will thus be seen that by twisting the bendable wire 7 the distance between the lens holding members 2 may be regulated to accommodate the pupillary distance of the wearer and due to the staple 5 and the link 6 connecting the bendable member 7 one lens holding member 2 may be folded with respect to the other thus providing a bridging member that may not only be shortened or lengthened simply by twisting but one that will maintain its adjustment until it is deliberately twisted again for some other adjustment. The nose engaging member 8 may be left off if desired. The link 6 also may be left off if desired, in which case the bendable wire 7 would pass through the staple 5. The bending out of the staple 5, as shown in Fig. 3, provides means by which the nose engaging member may be kept out allowing more room for the nose.

In the modification shown in Fig. 6 the staple 5 and the link 6 are used as in the case shown in Figs. 1 and 2, but instead of a single bendable wire 7 as shown in Fig. 1 a bundle 10 of wires 9 is used, being slipped through the link 6 as is the wire 7. The ends 10, however, of the bundle of wires 9 are passed into the retaining member 11 and soldered or otherwise held in place. The distance between 15 the lens holding members 2 is regulated exactly the same as in the case of the device shown in Fig. 1, that is, by twisting the loops of the bundle 9 until the required pupillary distance is obtained.

From the foregoing description it will be seen that I have provided simple, efficient and economical means for adjusting the distance between the lens holding members of an ophthalmic mounting by which the pupillary distance may be maintained and have also provided a flexible arrangement whereby one lens holding member may be folded with respect to the other.

Having described my invention, I claim:

1. In a device of the character described, a pair of lens holding members each having an eyelet connection on their nasal sides, a loose link connected to each eyelet and an endless ductile wire link extending through 55 the links, the two sides of the ductile link

being twisted together in the form of a spiral twist extending transversely in direction between the lens holding means.

2. In a device of the character described, a pair of lens holding members each having a bridge connection on their nasal sides and a bridge member holding said bridge connections of the lens holding members in alignment, said bridge member comprising a ductile wire link having its two sides twisted together in the form of a spiral twist extending transversely in direction between the lens holding means.

HARRY H. STYLL.
